2 Claims. (Cl. 30—34)

1

Dry shavers with two or more shearheads arranged in parallel relation, to achieve a closer shave, are known.

In shaving operation the first shearhead has a pulling action on the skin and the second shearhead follows over the stretched skin. With the stretching of the skin the hair or stubble tends to assume positions vertical to the skin surface and also projects more out of the pores, which makes it possible, that the stubble cut by the advancing shearhead may be cut deeper by the following shearhead.

This stretching action on the chin is different according to the distance between the shearheads, also according to the condition of the skin and the contour of the face. The description of the invention shows that these possibilities have been taken into consideration. The invention consists of a multiple head dry shaver, comprising at least two independent shaving heads or assemblies, which shaving heads are not in parallel relation to each other.

With such an arrangement of the shearheads it is possible to shave the different parts of the face with the skin stretched differently, according to one's desire. According to the angle and direction in which the shaver is held and moved, it is possible to choose for each part of the face the corresponding best stretching of the skin.

Preferably shearheads are taken into consideration, having an outer stationary cutter cooperating with a reciprocable inner cutter in such a way that the shearing action takes place not openly, but within the guard, which is at the same time the outer cutter. Such constructions, where the outer cutter forms a guard, make it possible to press the shearhead harder against the skin, without injury and therefore they allow a greater stretching of the skin. The slots in these outer cutters are continuous, as such an arrangement takes good care of the skin, compared with interrupted slots or guard openings which are arranged like a sieve. Such sieve cutter guards will bring positively into vertical position the hair that enters the sieve holes, however they exert an unpleasant pressure on the stubble which does not enter the holes. Continuous slots have the disadvantage, that strong, rather horizontal stubble cannot be sufficiently pulled up to a vertical position and therefore the inner cutter cannot cut them, as long as the slots are guided over the stubble in the same direction as the stubble lies on the skin. Such disadvantages associated with outer cutter guards, where the slots go right through, are eliminated by the present

2

invention. With this invention the strong stubble which goes right through the first shaver head without being cut, is pulled vertically by the inclined position of the second shearhead. This second shearhead is at an angle with the line of motion of the first shearhead and therefore the hair has no way to escape the inner cutter. Stubble that goes in an inclined position through the opening of the cutters, may be caught more securely and lifted up more cautiously with shearheads having continuous slots than with those having interrupted slots.

With shearheads not in parallel relation to each other the skin is stretched in different directions, when the shearheads are in motion, according to the direction of this motion the skin is either stretched by the first shearhead in a straight and by the second shearhead in an inclined direction, or in the reverse order. The result is that the stubble is pushed up to a vertical position from different directions.

Furthermore if the shaver moves over the skin with the ends of the shearheads near together, the effect is similar to the effect of a plough, as the skin is very much stretched apart. Moved in the opposite direction the skin may be raised by the shearheads, wherever desired, which is an advantage for certain growth of hair, as it may pull up the stubble to a different position. The shearheads may be of a straight construction, or curved lengthwise. Those shearheads with the cutting part curved lengthwise and concave have the further advantage with an inclined arrangement of the shearheads, that according to the angle with which the shaver touches the skin, either the part where the shearheads are further apart or the part where the shearheads are nearer together can be used, as desired.

Therefore it is possible to shave the different parts of the face with the distance of the shearheads best suited and chosen for any particular shaving operation. Such lengthwise curved shearheads have the added advantage that they stretch the skin to an inside arch and with it the skin is stretched in two directions for the trailing shearhead.

This inclined relation of the shearheads governs the stretching of the skin according to the angle with which they touch the skin and with it also the crosswise stretching of the skin works in a different angle, according to the direction in which the shaver is moved. The result is, that even with moving the shaver back and

forth in the same direction the stubble is pushed up in different directions.

In the accompanying drawings, which serve to illustrate several embodiments of this invention

Fig. 1 is a front elevation partly in section

Fig. 2 is a view in side elevation of Fig. 1

Fig. 3 is a top plan view of Fig. 1

Figs. 4 and 5 are variations of the invention in a top plan view.

The upper part of the shaver, seen in Figs. 1 and 2 shows two shearheads 1 and 1' in an inclined position relative to each other in relation to their distance apart.

Each shearhead has a hollow stationary guard 2 these guards have transverse slots which provide the shearing edges and thus constitute outer cutters and each having an inner cutter 3, reciprocated through lever 4 with round pin 5 and collar 6, which collar may turn and move up and down. This collar presses with spring 7 the inner cutter against the guard 2. The inner cutter and the outer cutter or guard are with their cutting surfaces curved lengthwise in a vertical plane passing through the longitudinal axis of the cutter, like a segment and have the purpose of stretching the skin lengthwise when the shaver touches the skin and furthermore, according to the inclination of the shaver and the pressure with which the shaver is moved over the skin, only a part of both shearheads will work, with the result that, as desired, the different parts of the face can be shaved with a different distance of the shaver heads in relation to each other.

It is understood that this arrangement of the shaver heads covers also straight shearheads as used on standard shavers, so to speak in an inclined position in relation to the shearhead levels. Fig. 1 shows the shaver in relation to skin A and skin B, drawn with dots. It is obvious that the position of the shaver in relation to skin part A results in a different distance of the shaverheads, than the one, resulting from using the shaver on skin part B, because the distance of the shearhead ends varies with the inclination with which the shearheads touch the skin. Fig. 4 shows a shaver with shearheads 1, 1' and 1'' arranged in such a distance to each other, that the two outside shearheads are parallel to each other, the shearhead in the middle however is in an inclined position in relation to the two outside shearheads. Another variation with three shearheads is seen in Fig. 5 where all three shearheads are arranged in an inclined position in relation to each other. Other variations are possible as the arrangement of more than 3 shearheads whereby at least two or all are in any desirable inclination to each other.

The movable cutters of the shearheads may be operated separately or together with one lever.

An example how one lever can move different cutters is seen in Fig. 1. Lever 4 is provided in this case with two lever pins 5, one in back of the other, of which only one is seen in the drawing.

This example shows that the inclination of the shearheads causes the inner cutters to move in a pointed angle in relation to the direction of motion taken by the lever, therefore the collar 6 moves in groove 8 of the inner cutter and has apart from the longitudinal motion also a small crosswise motion in relation to the inner cutter. Friction is eliminated by the fact, that collar 6 can turn on lever pin 5.

15 The different drawings of shearheads show separate shearhead units, that is each shearhead has a separate outer cutter and belonging to it a separate inner cutter and means to attach and lock the unit to the shaver. Furthermore 20 Figs. 1 to 3 show that each shearhead is provided with closure flaps for closing the open ends of the outer cutter and adapted to open for the removal of the severed hair tips and means permitting of easily opening and closing single 25 handed the closure flaps of each cutter head.

Having thus described the invention, what is claimed is:

1. In a dry shaver, a handle, a plurality of elongated shearheads mounted on said handle in proximity to each other, said heads having their longitudinal axes arranged at angles with respect to each other and being farther apart at one end than at the other.
2. In a dry shaver, a handle having a plurality of elongated shearheads mounted thereon in proximity to each other, said heads having their longitudinal axes arranged at angles with respect to each other and being farther apart at one end than at the other said shearheads being provided with outer hollow guards, which are provided with slots extending transversely of the longitudinal direction of extent of the respective heads, whereby the slots of the respective heads are angularly disposed relative to each other.
